CLAIM

The ornamental design for a faucet escutcheon, as shown and described.

DESCRIPTION

FIG. 1 is a top, front, and left side perspective view of a faucet escutcheon showing my new design;

FIG. 2 is a front elevational view thereof;

FIG. 3 is rear elevational view thereof;

FIG. 4 is a top plan view thereof;

FIG. 5 is a bottom plan view thereof; and,

FIG. 6 is a left side elevational view, the opposite side being a mirror image thereof.

The broken line showing is for illustrative purposes only and forms no part of the claimed design.
